UNITED STATES PATENT OFFICE.

SAM H. LIBBY, OF BLOOMFIELD, NEW JERSEY, ASSIGNOR TO GENERAL ELECTRIC COMPANY, A CORPORATION OF NEW YORK.

CONTROL FOR GLIDING SWITCHES FOR OVERHEAD MONORAIL TRAMWAYS.

Application filed April 26, 1922. Serial No. 556,656.

This invention relates to improvements in the control of switches for use in connection with overhead monorail tramways or runways, on which traveling cranes or hoists are operated.

It sometimes happens that the layout of tracks is such as to prevent the use of tongue switches, owing to short curves or confined space. In my prior Patent No. 1,078,051, 10 dated November 11, 1913, I have described and claimed an arrangement in which the "points" or connecting sections of rails are secured upon a frame which slides bodily on ways transverse to the tracks. Any given 15 rail sections may thus be aligned with any given pair of stub ends of trackage. The frame 18 is shifted by an electric motor controlled by a limit switch which can be connected with the trolley conductor by the 20 crane man on an approaching crane and is suitably geared to the motor so that it rotates therewith and breaks the motor circuit only when the gliding switch has reached the position selected by the crane man.

25 The present invention is directed to an improvement of my prior patented control. The arrangement as shown and described in my said patent while perfectly operative leaves something to be desired for certain 30 special conditions of which I shall mention one by way of example. In the patented arrangement, the motor circuit is closed directly by means of levers and contact shoes pivoted on each side of the cab. Such a 35 scheme necessitates conductors adjacent the stub ends of the monorail long enough to keep the circuit through the motor closed during the whole time that the gliding switch requires for its maximum movement, 40 and furthermore requires that the operator maintain his hold on the contact lever until the gliding switch has completed its movement to the desired position. In some runway layouts there are places where the 45 switches and crossovers are so close together that a sufficiently long conductor could not be installed.

In accordance with the present invention, 50 I provide an arrangement whereby the conductors disposed on each side of a stub end of the runway may be comparatively short, and whereby the operator need only close 55 momentarily a manually operated switch on a side of the cab so as to energize the motor to operate the gliding switch, the circuit for

the motor being maintained through the limit switch until the gliding switch has reached the desired limit of operation. When the cab is adjacent the short conductors on each side of a stub end of the monorail, if the operator desires that the gliding switch shall be operated, he need merely press a push button momentarily and then direct his attention to other matters. The gliding switch will be operated by the motor 60 until the proper connection of the monorail sections has been established by the gliding switch and the motor will then be automatically deenergized.

For a proper understanding of my invention reference is had to the accompanying drawings wherein I have illustrated the invention in a very simplified diagram in order to explain the principles thereof. Fig. 1 of the drawings shows a control arrangement for a gliding switch for connecting the stub ends of the monorail in various relations, and Fig. 2 shows one end of a traveling crane. Referring to the drawings, the gliding switch 10 is connected by an arrangement (not shown) so as to be operated by means of the electric motor which is shown as of the direct current type having an armature 11 and a split field winding having two oppositely wound sections 12 and 13, 70 one of the field winding sections being provided for one direction of motor operation and the other field winding section for the opposite direction of motor operation. The gliding switch 10 is adapted to connect the stub ends of the sections 14 and 15 of the monorail, as shown, or in its other position to connect the stub ends of the sections 14 and 16. 75

The motor is controlled by means of the pair of electroresponsive reversing contactors 17 and 18, and the extent of the operation of the motor, and thus the gliding switch is governed by means of the limit switch 19 which is operated synchronously with the movement of the gliding switch by any suitable means. The mechanical connections between the motor, the gliding switch and the limit switch have not been shown since those skilled in the art will readily supply a suitable arrangement. As indicated in the drawing, a pair of suitable power conductors extend along the monorail track and the comparatively short conductors 20 and 21 are disposed in the proximity of 80 85 90 95 100 105 110

the stub end of the monorail section 14, and the other stub ends of the monorail sections are also provided with similar short conductors. A contact mechanism connected with but insulated from the traveling crane is located at each side of the cab so as to make engagement with one of the power conductors and the corresponding short conductors. Thus, for example, the contact 22 is adapted to make engagement with the positive power conductor and the short conductor 20 and the contact 23 is adapted to make engagement with the negative power conductor and the short conductor 21 on the opposite side of the monorail. The push buttons 24 and 25 are located on opposite sides of the cab so that the operation of the gliding switch will be in the direction determined by the particular push button switch which is closed by the operator.

When the reversing contactor 17 closes it establishes a maintaining circuit for its winding through the auxiliary switch 26 associated with the contactor and the limit switch 19, and when the reversing contactor 18 closes it establishes a maintaining circuit for its winding through the auxiliary switch 27 and the limit switch 19.

As thus constructed and arranged the operation of the invention is as follows: Assume that the crane has moved to such a position that the contact 22 is in engagement with the short conductor 20 as shown in Fig. 1 and that the operator desires that the stub ends of the monorail sections 14 and 16 shall be connected by means of the gliding switch 10. The operator will close the push button switch 24, thereby energizing the contactor 17 to close through a circuit from the plus conductor, through contacts of the push button 24, contact 22, short conductor 20, through the winding of the contactor 17 and the segments 28 and 29 of the limit switch 19 to the negative supply conductor. The contactor 17 in closing, closes the auxiliary switch 26 so that the winding of the contactor 17 is thereby maintained closed through the limit switch 19, through a circuit which is independent of the push button 24. The push button 24 may then be released and the contactor 17 will nevertheless remain closed. The closing of the contactor 17 energizes the motor through the split field section 12 to operate the gliding switch 10 and the limit switch 19 synchronously therewith until the segment 29 of the limit switch breaks contact with its corresponding contact finger. This will be when the stub ends of the monorail sections 14 and 16 have been connected through the gliding switch 10. The motor is thereby deenergized at its limit of operation and the direction contactor 17 is also deenergized. The opening of the contactor 17 causes the auxiliary switch 26 to open and this contactor can not be again

energized until the limit switch has returned so that a circuit may be established through the segments 28 and 29 thereof.

Assume that the stub ends of the sections 14 and 16 are thus connected through gliding switch 10 and that it is desired to connect the stub ends of the sections 14 and 15 of the monorail. The push button 25 will be momentarily closed by the operator, thereby energizing the direction contactor 18 to close. When the direction contactor 18 closes, the maintaining circuit for the winding of this contactor is established through the auxiliary switch 27 and the segments 30 and 31 of the limit switch. The motor will be energized with the section 13 of the split field in circuit so as to operate in the reverse direction from that previously described. The operator need make only a momentary contact with the push button 25 and then direct his attention to other matters in the operation of the crane. When the gliding switch has been operated to the position shown in Fig. 1, the contactor 18 and the motor will be deenergized at the segment 30 of the limit switch. The maintained circuit for this contactor is also opened by the opening of the contactor.

With the arrangement above described, the operator need merely press a push button to cause the gliding switch to move to the desired position and then proceed with his other duties in the operation of the crane. Furthermore, the conductors adjacent the stub ends of the sections of the monorail may be comparatively short and the crane may proceed past and out of contact with these sections after the operator has pressed the correct push button for the desired direction of operation for the gliding switch.

In accordance with the provisions of the Patent Statutes, I have described the principle of operation of my invention together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. In a monorail tramway system, the combination of a plurality of tracks having stub ends and a traveling crane car operating thereon, a gliding switch operable between a plurality of positions for connecting the stub ends of the tracks in various relations to permit operation of the crane car over different routes, a reversible electric motor for operating said switch between said positions, means including a plurality of selectively operable push buttons on the traveling crane car and cooperating control conductors along the stub ends of the tracks

for energizing the motor to start operation of the gliding switch to each of said positions upon a momentary operation of a corresponding push button, and means including a limit switch operated responsively to movement of the gliding switch for maintaining the motor energized independently of said first means until the gliding switch is operated to the selected position.

10 2. In a monorail tramway system, the combination of a plurality of tracks having stub ends and a traveling crane car operating thereon, a gliding switch operable between a plurality of positions for connecting the stub ends of the tracks in various relations to permit operation of the crane car over different routes, a reversible electric motor for operating said switch between said positions, a conductor on each side of a stub

end of said tracks, electroresponsive motor 20 reversing switch mechanism connected to said conductors, contacts on the traveling crane car located in sliding relation with said conductors, a plurality of selectively operable push buttons cooperating with said 25 sliding contacts to establish a circuit for energizing the said motor to start operation of the gliding switch to each of said positions upon a momentary operation of the corresponding push button, and means including a limit switch operated responsively to movement of the gliding switch for maintaining the motor energized independently of said conductors until the gliding switch is operated to the selected position.

In witness whereof, I have hereunto set my hand this 24th day of April 1922.

SAM H. LIBBY.

Certificate of Correction.

It is hereby certified that in Letters Patent No. 1,588,244, granted June 8, 1926, upon the application of Sam H. Libby, of Bloomfield, New Jersey, for an improvement in "The Control for Gliding Switches for Overhead Monorail Trainways," an error appears in the printed specification requiring correction as follows: Page 1, line 17, strike out the numeral "18"; and that the said Letters Patent should be read with this correction therein that the same may conform to the record of the case in the Patent Office.

Signed and sealed this 20th day of July, A. D. 1926.

[SEAL.]

M. J. MOORE,
Acting Commissioner of Patents.
